UNITED STATES PATENT OFFICE

EDWIN W. NORTH, OF ROCKFORD, ILLINOIS, ASSIGNOR TO NATIONAL LOCK CO., OF ROCKFORD, ILLINOIS, A CORPORATION OF DELAWARE

SLIDING DOOR LOCK

Application filed October 27, 1930. Serial No. 491,330.

This invention relates to locks of the type particularly well adapted for use on sliding doors such as show case doors and the like.

As a primary object of this invention, it provides such a lock which requires a minimum amount of cutting of the door frames and may therefore be readily installed, which normally assumes an unlocked position and which may be locked by merely pressing the bolt inwardly without the use of a key, the key merely being necessary for unlocking.

It is also an object of this invention to provide a lock having these features and which will require few parts and which may be manufactured economically particularly in large quantities.

Other novel features of this invention will be apparent from the following description given in connection with the drawing in which:

Fig. 1 is a longitudinal section through a lock showing the same applied to two door members and in locked position.

Fig. 2 is a section on line 2--2 of Fig. 1.

Fig. 3 is a longitudinal section of the lock removed from a door and illustrating the same in unlocked position.

Fig. 4 is an elevation of one of the disc members of the lock.

Fig. 5 is an elevation of a spacer member.

Fig. 6 is an elevation of the tumbler.

Fig. 7 is an elevation of a lock washer.

Fig. 8 is an elevation of the key for use in the lock.

Referring more particularly to the drawing, it will be seen that the lock comprises a cylinder 1 terminating at one end in a slightly enlarged circular recessed selvedge 2. The cylinder with its selvedge end serves as

a housing or casing for the entire lock. Mounted for reciprocatory movement in an axial direction within the cylinder is a plunger-like bolt 3. The bolt 3 is provided with a sleeve-like member 4 on one end thereof.

The sleeve is secured to the bolt for reciprocal movements therewith by being provided at one end with an annular recess 5 to receive an end flange 6 formed on the end of bolt 3. The sleeve is spun over at its end as at 7 to lock the flange 6 within recess 5 and

yet permit rotation of the bolt relatively to the sleeve. The sleeve is also provided with a flange 8 upon its inner end which flange serves as a bearing guide slidable within the cylinder the latter having a flange 9 spun over upon the end thereof. Flange 9 engages flange 8 and limits the movement of the bolt in one direction. A U-shaped lock washer 10 engaging a circular groove 11 formed in a bolt 3 intermediate its ends further prevents axial movement between sleeve 4 and bolt 3.

As can be seen the sleeve 4 and bolt 3 are reciprocally mounted within cylinder 1 and are of such length that when in locked position the bolt extends beyond the cylinder at the selvedge end and when in unlocked position the sleeve extends beyond the other end of the cylinder where it may be engaged to be moved into locking position. The bolt and sleeve are normally urged to the left as viewed in Figs. 1 and 3 or to unlocked position by a compression spring 12 surrounding bolt 3 within the cylinder and placed under compression between lock washer 9 and a disc 13, the latter being disposed within the recessed selvedge end 2 of cylinder 1.

In order to retain bolt 3 in locked position the bolt is provided with an annular groove 14. This groove is engaged by a pivoted lever tumbler 16 pivotally secured between disc 13 and a similar opposed disc 17. The two discs are held in spaced relation by a segmental spacer disc 18, the latter being of sufficient thickness to provide a space between discs 13 and 17 within which the tumbler may pivot into and out of latching position. Tumbler 16 is constantly urged into latching position by a leaf spring 19.

As can be seen from the drawing, the two discs 13 and 17, the spacer disc 18 and the tumbler 16 are all secured within the recess of selvedge 2 by means of rivets 21 which extend through the foregoing members and the selvedge.

In order to unlatch the bolt and permit spring 12 to withdraw the same into unlocked position, the bolt is slotted longitudinally for substantially its entire length to receive a key 22 of sufficient length to extend

substantially the full length of the groove and engage tumbler 16. Upon insertion of the key into bolt 3 and rotation thereof with the key therein, the key will engage lever 16 5 and eject it from groove 14. This will permit spring 12 to withdraw bolt 3.

In order to prevent rotation of sleeve 4 the cylinder is formed with a pair of diametrically disposed longitudinal depressed ribs 10 23 arranged to slide in diametrically disposed slots 24 formed in sleeve 4 and lock washer 10.

It is obvious from the foregoing that there has been provided a lock which, due to the 15 minimum number of parts employed and the simple construction of these parts, may be manufactured very economically, particularly in large quantities.

To install the lock it is merely necessary 20 to drill a single hole in each of the doors one to receive the thimble or keeper and one to receive the lock. The hole for the latter member need only be counterbored to receive the selvedge end of the cylinder thus eliminating the necessity of complex mortising.

In operation it is merely necessary to press bolt 3 until tumbler 16 engages in groove 14. That is, it is not necessary to insert a key or turn a bolt or cylinder to latch or lock the 25 bolt. To unlatch the bolt it is merely necessary to insert the key and rotate the bolt after which the latter will be withdrawn by spring 12.

It is obvious that many changes may be 30 made in the details of construction without departing from the spirit and scope of the invention as defined in the following claims.

I claim:

1. A sliding door lock comprising a cylinder, a sleeve telescopically mounted within said cylinder for reciprocating but non-rotating movements therein, a bolt within said sleeve, means for locking said bolt to said sleeve for reciprocating movements there- 40 with, and rotary movements therein, said bolt extending beyond one end of said cylinder when in locked position and the other end when in unlocked position, means for locking said bolt when in one position, and 45 a spring arranged to normally withdraw said bolt from extended position when unlocked, said locking means being releasable by a key upon rotation of said bolt with a key inserted therein.

2. A sliding door lock comprising a cylinder, a sleeve telescopically mounted within said cylinder for reciprocating but non-rotating movements therein, a slotted bolt within said sleeve, a lock washer engaging 50 said sleeve and the slot in said bolt for locking said bolt to said sleeve whereby said bolt will be secured to said sleeve for reciprocating movements therewith and rotary movements therein, said bolt extending beyond one end of said cylinder when in locked po- 55

sition and beyond the other end when in unlocked position, means for locking said bolt in locked position, and a spring arranged to normally withdraw said bolt from locked position, said locking means being 70 releasable by a key upon rotation of said bolt with said key therein.

3. A sliding door lock comprising a cylinder, an annularly grooved bolt mounted within said cylinder for reciprocating movements 75 therein, said bolt extending beyond one end of said cylinder when in locked position and beyond the other end when in unlocked position, a sleeve telescopically mounted within said cylinder and surrounding said bolt, a spring arranged to normally withdraw said bolt from extended position, and a lock washer arranged to enter the groove of said bolt to lock said bolt to said sleeve for reciprocating movements therewith while permitting rotary movements therein.

4. A sliding door lock comprising a cylinder, a bolt having a pair of annular grooves therein mounted within said cylinder for reciprocating movements therein and adapted 90 to extend beyond one end thereof when in locked position and the other end thereof when in unlocked position, a sleeve telescopically mounted within said cylinder and surrounding said bolt, a spring arranged to normally withdraw said bolt from extended position, a lock washer engaging one groove of said bolt to secure said bolt to said sleeve for reciprocating movements therewith and rotary movements therein, and a locking tumbler arranged to enter the other groove of said bolt to lock said bolt in extended position.

5. A sliding door lock comprising a cylinder terminating at one end in an enlarged selvedge, a bolt having a groove therein mounted within said cylinder for reciprocating movements therein and adapted to extend beyond one end thereof when in one position and the other end when in the other position, a spring arranged to normally withdraw said bolt from extended position and a pivoted locking tumbler disposed within said selvedge portion of the cylinder and arranged to enter said groove to lock said bolt in extended position.

6. A sliding door lock comprising a cylinder terminating in an enlarged selvedge, a bolt having a groove therein mounted within said cylinder for reciprocating movements therein and adapted to extend beyond one end thereof when in one position and the other end when in the other position, a spring arranged to normally withdraw said bolt from extended position, a pair of discs disposed within said selvedge portion, and a locking tumbler disposed between said discs and arranged to enter said groove to lock said bolt in extended position, said tumbler being 120 125 130

releasable by the insertion of a key in said bolt.

7. A sliding door lock comprising a cylinder, a supporting sleeve telescopically mounted within said cylinder for reciprocating movements therein, a bolt having a groove therein rotatably secured within said sleeve for reciprocating movements therewith, said bolt being adapted to extend beyond one end of said cylinder when in locked position and beyond the other end when in unlocked position, a spring arranged to normally withdraw said bolt from locked position and a locking tumbler within said cylinder and arranged to enter said groove to secure said bolt in locked position, said lever being releasable by a key inserted in said bolt.

8. A sliding door lock comprising a cylindrical casing terminating at one end in an enlarged circular flange having an annular rim extending therefrom, a bolt mounted within said cylinder for reciprocating movements therein and adapted to extend beyond the flanged end thereof when in locked position and beyond the other end when in unlocked position, means disposed within said flanged end for securing said bolt in locked position, and a spring arranged to normally withdraw said bolt from extended position when unlocked.

9. A sliding door lock comprising a cylindrical casing terminating at one end in an enlarged circular flange having an annular rim extending therefrom, a sleeve telescopically secured to said casing, means for preventing rotation of said sleeve within said casing, a bolt having a groove therein secured to said sleeve for reciprocating movements therein, said sleeve being mounted within said cylinder for reciprocating movements therein, said bolt being adapted to extend beyond one end of said cylinder when in latched position and the other end when in unlatched position, a spring arranged to normally withdraw said bolt from extended position, and a locking tumbler within said cylinder and arranged to enter said groove to lock said bolt in extended position, said tumbler being releasable by a key inserted in said bolt.

50 In witness of the foregoing, I affix my signature.

EDWIN W. NORTH.
